UNITED STATES PATENT OFFICE

158,632

XYLOPHONE

Harry Zimmerman, New York, N. Y.

Application May 12, 1949, Serial No. 2,608

Term of patent 14 years

(Cl. D56—1)

To all whom it may concern:

Be it known that I, Harry Zimmerman, a citizen of the United States, residing at New York, in the county of New York and State of New York, have invented a new, original, and ornamental Design for a Xylophone, of which the following is a specification, reference being had to the accompanying drawing, forming part thereof.

In the drawing the figure is a perspective view of a xylophone, showing my new design.

I claim:

The ornamental design for a xylophone, substantially as shown.

HARRY ZIMMERMAN.
